PHOTOGRAPHIC PROCESSING APPARATUS
WITH A TUBULAR DEVELOPER DISPENSER
Edwin H. Land, Cambridge, Mass., assignor to Polaroid
Corporation, Cambridge, Mass., a corporation of
Delaware
Filed Aug. 23, 1961, Ser. No. 133,343
5 Claims. (Cl. 95—89)

This invention relates to photographic apparatus for 10 treating exposed photosensitive sheet material with a fluid by distributing the fluid between the photosensitive sheet and another sheet superposed therewith.

The present invention is concerned with photographic apparatus of the type in which a fluid processing composition is distributed between a pair of superposed photographic sheets by advancement of the sheets relative to and between a pair of juxtaposed pressure-applying members. In my copending United States patent application Serial No. 820,266, filed June 15, 1959, now Patent No. 3,047,387, there is disclosed a system for providing a viscous photographic processing fluid between a pair of superposed photographic sheets of a film unit, for distribution between the sheets by the subsequent advancement of the film unit between a pair of juxtaposed pressure-applying members. This system is designed to provide a precisely predetermined quantity of the fluid in the form of a uniformly distributed elongated mass on, and extending from side to side of the area of, one of the two sheets over which the fluid is distributed, by movement of the sheet relative to the pressure-applying members in a direction transversely of the direction of elongation of the mass of fluid. The fluid is dispensed from a disposable elongated tubular container, very much like a drinking straw, positioned between the sheets by movement of the container in the direction of its elongation relative to and across the sheets while the container is being compressed. The fluid contents of the container are ejected from the open trailing end of the container onto one of the sheets in the form of a uniformly distributed elongated mass. This system of fluid dispensing offers the advantage of accurate control of fluid distribution, regardless of the rate at which the container is moved across the sheets and also results in ridding the film unit of the container, so that the container does not affect the subsequent distribution of the fluid between the sheets. The fluid, in most cases, includes a viscosity-increasing agent which hardens upon evaporation of the fluid medium (water) and other material, such as developers, which oxidize readily, and must be kept from contact with the air. Obviously, the very nature of the fluid, itself, is the basis for many of the problems involved in its dispensing.

An object of the invention is to provide, in a photographic apparatus of the type described for processing a succession of exposed areas of a photosensitive sheet, novel and improved means, including a tubular fluid dispensing member, for dispensing successive predetermined quantities of said processing fluid on one of a pair of superposed photosensitive and second sheets, for distribution between successive exposed areas of the photosensitive sheet and areas of the second sheet superposed therewith.

Another object of the invention is to provide fluid dispensing means of the type described which can be operated manually to give uniform results.

A further object of the invention is to provide fluid dispensing means as described, which is simple and inexpensive in its construction and reliable in its operation.

Other objects of the invention will in part be obvious and will in part appear hereinafter.

The invention accordingly comprises the apparatus pos-

2

sessing the construction, combination of elements and arrangement of parts which are exemplified in the following detailed description taken in connection with the action which will be indicated in the claims.

For a fuller understanding of the nature and objects of the invention, reference should be had to the following detailed description taken in connection with the accompanying drawings wherein:

FIGURE 1 is a schematic sectional view of photographic apparatus incorporating the invention;

FIG. 2 is a perspective view, partially in section, illustrating the fluid dispensing means of the invention;

FIG. 3 is a plan view of the fluid dispensing means;

FIG. 4 is a vertical section taken substantially along the line 4—4 of FIG. 3;

FIGS. 5A and 5B are sectional views taken substantially along the line 5—5 of FIG. 3 illustrating two positions of components of the fluid dispensing means;

FIG. 6 is a fragmentary perspective view illustrating another embodiment of components of the fluid dispensing means; and

FIGS. 7A and 7B are vertical sectional views taken substantially along the line 7—7 of FIG. 6 illustrating two positions of the components of FIG. 6.

The fluid dispensing means of the invention is incorporated in photographic apparatus wherein successive areas of a photosensitive sheet are exposed and processed. Apparatus of this type includes, for example, cameras, printing apparatus, and document copying apparatus such as shown and described in the copending United States patent application of Edwin H. Land et al., Serial No. 133,483, filed August 23, 1961, in which the exposed areas of the photosensitive sheet are advanced into superposition with areas of a second sheet and the superposed sheets are moved between a pair of juxtaposed pressure-applying members for distributing a processing fluid between the superposed areas of the sheets. This processing of the exposed photosensitive sheet may be designed to produce a positive image on the second sheet by a silver halide diffusion transfer-reversal process such as described in U.S. Patent Nos. 2,543,181, issued February 27, 1951, and 2,662,822, issued December 15, 1953, both in the name of Edwin H. Land. A predetermined quantity of processing fluid to be distributed between each pair of areas of the photosensitive and second sheets is provided for distribution on one of the sheets adjacent an edge of the area thereof over which the fluid is to be distributed, in the form of a uniformly distributed elongated mass extending substantially from side to side of the area. The fluid dispensing means of the invention is designed to provide successive predetermined quantities of the fluid in this manner for distribution between successive superposed areas of the photosensitive and second sheets as each pair of areas approaches a pair of juxtaposed pressure-applying members between which the sheets are moved for distributing the fluid from the elongated mass. The fluid dispensing means is required to dispense a precise quantity of fluid for distribution between each pair of superposed areas, to distribute the fluid in exactly the same manner each time, regardless of variations in the manner in which it is actuated, and to be uniformly reliable in its operation.

Reference is now made to FIGURE 1 of the drawings wherein there is illustrated schematically photographic apparatus for exposing and processing a photosensitive sheet and incorporating the invention, and to FIGURES 2 through 7 which illustrate the fluid dispensing apparatus. The apparatus embodying the invention comprises means shown as a spool 10 for holding a supply of photosensitive sheet material 12. Guide means, designated 14, are provided for locating successive areas of the photosensitive sheet in position for exposure to actinic light

by a suitable exposure means such as a lens, designated 16, illustrated as being joined to the guide means by a bellows 18; it being understood, however, that the exposure and guide means may include any of the conventional systems for exposing photosensitive sheet material, including exposure means of the type employed in document copiers, such as described in the aforementioned application Serial No. 133,483.

The apparatus includes a second spool 20 for holding a supply of a second or print-receiving sheet 22 and a pair of juxtaposed pressure-applying members, in the form of rolls 24, between which the photosensitive and second sheets are advanced in superposition for distributing a processing fluid between the sheets to form a sandwich. The apparatus also includes a pair of feed rolls 26 for engaging the sandwich and advancing the sheets through the apparatus and means (not shown) of a conventional type, for driving the feed rolls and controlling and coordinating the functions of the various components of the apparatus.

The fluid dispensing means, in the form shown, comprises means, in this case guide means 14, for supporting a section of photosensitive sheet 12 adjacent the bite of rolls 24. The fluid distributing means is designed to distribute a predetermined quantity of the processing fluid in an elongated mass across this section of photosensitive sheet 12 closely adjacent rolls 24, intermediate the rolls and the leading edge of an exposed area of the photosensitive sheet. The fluid dispensing means comprises an elongated tubular member 28 including a portion employed for fluid dispensing and having a substantially uniform cross section throughout its length. The tubular member, in the form shown, has a circular cross section. However, other cross sections are possible and considered to be within the scope of the invention, so long as the cross sectional area of the inner surface of the fluid dispensing portion of the tubular member remains constant throughout the length of the portion. The tubular member is formed of a flexible resilient material, such as rubber and organic plastics, which permits the tubular member to be bent and to be compressed, and which has sufficient resilience and elasticity to cause the tubular member to return to its original cross sectional configuration after a deforming force has been relieved. The fluid dispensing portion of the tubular member is open at one end to form a discharge mouth 30 and is connected at its other end to a container 32 having a capacity for sufficient processing fluid to completely fill the tubular member a plurality of times. The fluid dispensing portion of the container is designed to meter predetermined quantities of the processing fluid and is at least equal in length to the length of the elongated mass of fluid to be dispensed from the tubular member. This mass of fluid is preferably approximately equal to the width or transverse dimension of the area over which the fluid is distributed and the capacity of the container may, in one form, be sufficient to provide a predetermined quantity of the fluid on each of the exposed areas of photosensitive sheet 12 supplied on spool 10.

The processing fluid may be quite viscous, may contain a thickening agent which hardens upon evaporation of the fluid (water), and may contain materials, such as developing agents, which are readily oxidized. Container 32 is constructed to permit substantially all of the fluid contents of the container to be fed into tubular member 28 and, for this purpose, may be collapsible or include a collapsible wall, such as will permit the fluid contents of the container to flow into the tubular member under atmospheric pressure. In another embodiment, the container may be pressurized, for example, by the inclusion of a gas under pressure in the container tending to force the fluid to flow into the tubular member.

Ejection of the fluid contents of the tubular member through discharge mouth 30 onto photosensitive sheet 12 is accomplished by first positioning the tubular member

5 adjacent photosensitive sheet 12 and the bite of rolls 24, with the tubular member extending across sheet 12, with discharge mouth 30 disposed at one longitudinal edge of the sheet and the container located at the opposite longitudinal edge of the sheet. The tubular member is then moved in the direction of its elongation across the sheet away from mouth 30 while succeeding sections of the tubular member are compressed adjacent said opposite edge of the sheet for forcing the fluid contents of the tubular member therefrom through mouth 30. The quantity and distribution of the fluid ejected from the tubular member through mouth 30 is thereby made independent of the rate at which the tubular member is moved across the sheet, and is dependent only on the cross sectional area of the tubular member and the position of the tubular member during movement.

10 Means are provided for effecting the movement of the tubular member and supporting the tubular member during this movement. This means includes a spool or drum 20 mounted for rotation adjacent the side of the photosensitive sheet opposite discharge mouth 30, and having a substantially cylindrical circumferential surface with flanges at its ends. Spool 34 is rotatable about an axis perpendicular to the direction of movement of the container across the sheet, and substantially perpendicular to the plane of the section of the sheet on which the fluid is dispensed. The tubular member extends from discharge mouth 30 across sheet 12 and around a section of the cylindrical surface of spool 34 between the flanges to container 32, and movement of the tubular member across the photosensitive sheet to effect the discharge of the fluid contents of the tubular member can be accomplished by moving the container in a direction more or less parallel with the direction of movement of the photosensitive sheet. 15 This particular construction is preferred because it contributes to a reduction in the overall size of the apparatus which would not be possible if the container were moved, for example, in a direction parallel with the axes of rolls 24.

20 Means are provided for compressing the container as it is moved from the first position described, i.e., with the container and discharge mouth disposed adjacent opposite sides of the sheet, to a second position in which the discharge mouth is located adjacent the same side of the sheet as the container in the region of spool 34. This means comprises a pivotable pressure member 36 mounted adjacent spool 34 with one end extending toward and into engagement with a section of tubular member 28 located between the cylindrical surface of the spool and pressure member 36. Pressure member 36 is biased toward spool 34 by a relatively weak spring 38 and is essentially self energizing by virtue of the frictional engagement between the tubular member and the pressure member during movement of the tubular member from the first to the second position which tends to force the pressure member against spool 34 and thereby apply compressive pressure to the section of the tubular member located between the spool and pressure member. During movement of the tubular member in the opposite direction, i.e., from the second to the first position, frictional engagement between the tubular member and pressure member tends to pivot the pressure member away from spool 34 and thereby relieve the compressive pressure on the tubular member. The force of spring 38, of course, 25 is insufficient to cause the pressure member to compress the tubular member, the spring being provided for the sole purpose of retaining the pressure member in engagement with the tubular member to insure self-energization of the latter. As the tubular member is moved from the first to the second position thereof, the fluid contents of the portion of the tubular member intermediate the pressure member and the discharge mouth remain substantially stationary with respect to the tubular member, and are thereby ejected from the discharge mouth as the latter is moved 30 across the photosensitive sheet. The portion of the tubu-

lar member located to the opposite side of spool 34 and pressure member 36, i.e., between the spool and pressure member and container, becomes refilled with the fluid as the fluid is being ejected from the open end of the tubular member, and in this manner, the tubular member remains substantially full of the fluid at all times. Atmospheric pressure may prove sufficient, if the viscosity of the fluid is not too great, to cause the fluid to flow from container 32 throughout the length of the tubular member. However, pressurization of the container may be necessary in order to cause the fluid to flow from end to end of the tubular member, particularly, if the fluid is quite viscous.

Movement of the tubular member from the second to the first position is effected by the provision of a connecting element coupled with the tubular member in the region of its discharge mouth for pulling the end of the tubular member across the photosensitive sheet. This means comprises, in the form shown in FIGS. 2 through 7, a flexible connecting member 40, such as a cable, wire, or metal strip and a second spool or drum 42 mounted adjacent the side of the photosensitive sheet opposite spool 34 and providing means on which the connecting member is coiled when the tubular member is in the first position thereof. Spool 42 may be provided with a torsion spring type of return mechanism which causes the spool to recoil connecting member 40 after the latter has been withdrawn from the spool in order to return the tubular member to its first position from its second position.

The connecting member is coupled with the tubular member in such a way as not to interfere with the flow of fluid from discharge mouth 30. In the form shown in FIGS. 2 and 3, a pair of diametrically spaced ears 44 are provided on the outside of the tubular member adjacent the discharge mouth, and two relatively short connecting elements 46 are connected to the ears on opposite sides of the discharge mouth and are coupled with a link 48 secured to connecting member 40, the link serving to retain connecting elements 46 in their spaced positions.

In another embodiment shown in FIGS. 6, 7A and 7B, connecting member 40 is coupled with a collar 50 secured around the tubular member adjacent the discharge mouth thereof.

As previously noted, the tubular member is substantially filled with the fluid at all times, including the period when the tubular member is located in the first position thereof. For this reason, means are provided for closing the discharge mouth, when the tubular member is in the first position, to prevent loss of the fluid by leakage or evaporation through the discharge mouth. In the form shown in FIGS. 2, 3, 5A and 5B, this means comprises a pair of juxtaposed pressure members 52 having convergent facing surfaces defining a tapered channel 54 into which the discharge mouth is advanced from the position shown in FIG. 5A to the position shown in FIG. 5B, during movement of the tubular member from its second to its first position. Connecting member 40 extends through the channel and functions to pull the leading end of the tubular member into the channel during the last portion of the movement of the tubular member from its second to its first position, causing the discharge mouth to be compressed and closed. In another form of apparatus shown in FIGS. 6, 7A and 7B, the end portion of the tubular member comprising the discharge mouth projects through and beyond collar 50 and a tapered plug 56 is provided mounted adjacent the side of the photosensitive sheet and spool 42 in the path of movement of the discharge mouth, so that the latter is drawn from a position shown in FIG. 7A, into surrounding engagement with the tapered plug 56, to the position shown in FIG. 7B, during the terminal portion of the movement of the tubular member from its second to its first position. Both of the foregoing means for closing the discharge mouth remain stationary and permit the discharge mouth to open almost immediately as movement of the tubular member from its first position is commenced.

To effect the processing of an exposed area of the photosensitive sheet, the tubular member 28, filled with the processing fluid, is moved from its first position to its second position, thereby advancing discharge mouth 30 from one side of the photosensitive sheet across the photosensitive sheet to the other side thereof, while the fluid contents of the portion of the container extending across the sheet is ejected from the discharge mouth and disposed upon the photosensitive sheet in the form of the desired elongated mass. Movement of the tubular member is effected, for example, by engaging and moving container 32 against the bias of the spring windup mechanism of spool 42. In another embodiment (not shown), the container may be constructed to function as a spool on which the tubular member is coiled to effect movement of the tubular member from the first to the second position thereof. In this embodiment, the mechanism of the apparatus will include means for rotating the container so as to coil the tubular member around the exterior of the container. The apparatus could be further modified within the scope of the invention by utilizing the container itself as means around which the tubular member is coiled as one of a pair of pressure-applying members for compressing the tubular member and causing ejection of its fluid contents. Return of the tubular member from its second position to its first position is effected substantially automatically by the return spring mechanism of spool 42, and distribution of the processing fluid between the sheets is accomplished by advancement 30 of the sheets between the pressure-applying rolls 24, which cause the mass of fluid to be moved with respect to the sheets in a direction opposite the direction of movement of the sheets between the pressure-applying rolls. The tubular member is retained in its first position in readiness for subsequent operation for dispensing another quantity of the processing fluid on the photosensitive sheet. While the apparatus has been shown as being designed for dispensing a processing fluid on the photosensitive sheet, it is also contemplated that the fluid can be dispensed by the same mechanism on either the second sheet or on both sheets in the region where the sheets converge at the bite of the pressure-applying rolls. In this latter embodiment, the bite of the pressure-applying rolls would, of course, be located beneath the path of movement of the discharge mouth of the tubular member across the sheets.

Since certain changes may be made in the above apparatus without departing from the scope of the invention herein involved, it is intended that all matter contained in the above description or shown in the accompanying drawings shall be interpreted as illustrative and not in a limiting sense.

What is claimed is:

1. Photographic apparatus for treating successive exposed areas of photosensitive sheet material by distributing a fluid processing composition in contact with said exposed areas of said photosensitive sheet, said apparatus comprising, in combination, fluid distributing means for engaging said sheet and distributing a processing fluid in contact with said sheet during movement of said sheet relative to and in engagement with said means; and fluid dispensing means for dispensing a predetermined quantity of said processing fluid on said sheet adjacent said fluid distributing means in the form of a uniformly distributed elongated mass extending transversely of the direction of movement of said sheet relative to said fluid distributing means; said fluid dispensing means including an elongated tubular member having a substantially uniform interior cross section throughout a fluid dispensing portion thereof, said fluid dispensing portion of said tubular member being deformable by compression and having sufficient resilience to resume its original configuration upon removal of a deforming force applied thereto, said fluid dispensing portion of said tubular member being open at one end to provide a discharge mouth and being connect-

ed at its other end to a container having a capacity for sufficient fluid to substantially fill said portion of said member a plurality of times, said portion of said member being mounted for movement between a first position in which said portion of said member is located adjacent said sheet and extends from side to side thereof with said discharge mouth located adjacent one side of said sheet and said other end of said portion disposed adjacent the opposite side of said sheet, and a second position wherein said discharge mouth is located adjacent said opposite side of said sheet, means for moving said tubular member between said first and second positions so as to move said discharge mouth from side to side of said sheet, and means for deforming said portion of said member adjacent said opposite side of said sheet to effect the discharge of fluid contained within said portion of said member through said discharge mouth during movement of said member from said first to said second position.

2. The photographic apparatus of claim 1 including means for engaging said tubular member at said first position for closing said discharge mouth when said tubular member is in said first position.

3. The photographic apparatus of claim 2 wherein the last-mentioned means comprise a pair of pressure-applying members for engaging said one end of said tubular member.

4. The photographic apparatus of claim 2 wherein said last-mentioned means are located adjacent said one side of said sheet and are substantially fixed against movement with respect to said sheet and said juxtaposed members.

5. Photographic apparatus for treating successive exposed areas of a photosensitive sheet by distributing a fluid processing composition between said exposed areas of said photosensitive sheet and areas of a second sheet superposed therewith, said apparatus comprising, in combination, a pair of juxtaposed members for superposing said sheets and distributing a processing fluid between said sheets during movement of said sheets relative to and between said members; means for supporting a section of one of said sheets adjacent said pressure-applying members; and fluid dispensing means for dispensing a predetermined quantity of said processing fluid on said section of said one sheet between said sheets, in the form of a uniformly distributed elongated mass approximately equal

in length to the width of said areas and extending transversely of the direction of movement of said sheets between said members, adjacent the leading edges of successive superposed areas of said sheets; said fluid dispensing means including an elongated flexible tubular member having a substantially uniform interior cross section throughout its length, said tubular member being deformable by compression and having sufficient resilience to resume its original cross section configuration upon removal of a deforming compressive force applied thereto, said tubular member being open at one end to provide a discharge mouth and being connected at its other end to a container having a capacity for sufficient fluid to substantially fill said tubular member a plurality of times, said tubular member being mounted for movement in the direction of its elongation between a first position in which said tubular member is located adjacent said section of said one sheet and extends from side to side of said area thereof transversely of the direction of movement of said one sheet between said juxtaposed members with said discharge mouth located adjacent one side of said sheet and said container disposed adjacent the opposite side of said one sheet, and a second position wherein said discharge mouth is disposed adjacent said opposite side of said one sheet, means for moving said tubular member between said first and second positions so as to move said discharge mouth back and forth across said section of said one sheet from side to side thereof, means for engaging said tubular member adjacent said opposite side of said one sheet and compressing a portion of said tubular member to effect the discharge of fluid contained within said tubular member through said discharge mouth during movement of said tubular member from said first to said second position, the last-mentioned means being inoperative to apply compressive pressure to said tubular member during movement thereof from said second to said first position, and means for closing said discharge mouth when said tubular member is in said first position.
